Sewell H. Downs, Kalamazoo, Mich., assignor to Clarge Fan Company, Kalamazoo, Mich., a corporation of Michigan

Application October 17, 1957, Serial No. 690,726

4 Claims. (Cl. 230—130)

This invention relates in general to a multi-stage blower and, more particularly, to a type thereof having a pair of inlet boxes which are disposed between, and communicate respectively with, a pair of spaced single inlet blower housings, each of which contains a blower wheel mounted upon the same shaft structure.

A recognized need has long existed for air handling equipment capable of moving relatively large volumes of air at relatively high outlet pressures, without sacrificing efficiency and at a reasonable cost. Present conventional blower units are incapable of producing the desired pressures without exceeding permissible tip speeds and/or sound levels. As a result of this, centrifugal compressors are being used more frequently, particularly in multiple stages, to provide the higher pressures which are demanded. However, such compressors are presently made from carefully machined parts which are relatively costly to purchase originally and, also, are costly to maintain, particularly in heavy duty operations where replacements are often needed. Furthermore, the volume produced by such compressors is relatively small by comparison with the cost of the installation.

It has previously been recognized that, if two or more centrifugal blower units could be staged in an efficient manner, it would be possible to produce substantially larger pressures than are presently available with a single blower unit, while at the same time maintaining the lower cost and the higher volumes of centrifugal blowers, by comparison with compressors. It is also recognized that, if the air moving from one stage to another has rotational components around the blower wheel axis as it enters the blower unit of the higher stage, there will be a corresponding reduction in capacity. In one form of multiple blower installation, two or more conventional, otherwise independent, blower units are serially interconnected by the ducts connecting the outlet of one to the inlet of another. Where, for example, two blower units are so arranged, the space requirements are at least double, as compared with a single unit, and the costs are very materially increased. Even though the increased cost may be acceptable, the increased space requirements are frequently unacceptable.

Another type of multiple blower installation comprises a double width, double inlet, blower unit having inlet boxes on the opposite sides thereof. A divider plate encircles the double width wheel substantially co-planar with the center plate thereof, thereby dividing the double unit into two single units. However, this arrangement necessitates the use of a very large and heavy shaft and correspondingly heavy bearing structures. More specifically, the shaft must be large and strong, both because of its long span and because the blower wheel is mounted at the center of such span. Furthermore, because of the necessarily large diameter of the shaft at its center, the wheel hub must be correspondingly large and heavy. The oversized hub not only further aggravates the shaft size problem, but also produces a reduction in the performance of the blower wheel. Thus, not much is gained by using

such a structure, except for saving some space by eliminating two of the four bearing assemblies, which would be required by simply providing two separate units. There is no saving in cost because of the increase in cost of the oversized shaft, the oversized hub structure for the blower wheel and the oversized bearing structures required to support the oversized shaft. Furthermore, the resultant structure is relatively heavy and difficult to install, particularly where large units are required.

Another problem, which is characteristic of the double width assembly, arises when the two sides of the assembly are interconnected. As stated above, the double width blower housing is divided by a central wall which, at least in effect, produces two single width blower units. In order to stage these two units, the outlet from one blower unit must be connected by a duct to the inlet box of the other unit, which necessitates that the connecting duct pass around the other blower unit. Often, particularly in large installations, it is desirable, if not essential, that both blower units discharge in the same direction. Thus, the interconnecting duct must either block the outlet of the blower crossed over or it is necessary to make this cross-over through a very tortuous path, which not only adds to the cost of the installation, but also often introduces rotational components in the air flow which materially reduce the capacity of the unit and may even prevent its use.

Accordingly, a primary object of this invention has been the provision of a multi-stage blower structure capable of producing a relatively high total pressure with a minimum of loss in capacity and/or efficiency, with a minimum of increase in cost of fabrication and operation, and with an absolute minimum of space required for the installation.

A further object of this invention has been the provision of a two-stage blower construction wherein the operational and performance advantages of single blower units are retained, wherein the space required for the connections between, as well as with, the two blower units is held to an absolute minimum while the construction remains capable of variation in installation arrangements, and wherein the weight of the blower wheels is supported upon the shaft substantially adjacent to the shaft supporting bearings, thereby minimizing the size of the shaft required to support the wheels.

Other objects and purposes of this invention will become apparent to persons familiar with this type of equipment upon reading the following specification and examining the accompanying drawings, in which:

Figure 1 is a side elevational view of a two-stage blower assembly characterizing the invention.

Figure 2 is a top plan view of said two-stage blower assembly.

Figure 3 is a sectional view taken along the line III—III of Figure 2.

Figure 4 is a side view of a modified structure.

For the purpose of convenience in description, the terms "upper," "lower" and derivatives thereof will have reference to the two-stage blower assembly in its normal position of operation, as shown in Figures 1 and 3. The terms "inner," "outer," and derivatives thereof will have reference to the geometric center of the blower assembly and parts thereof.

General description

In order to meet the objects and purposes of this invention, including those set forth above, there has been provided a two-stage blower assembly comprised of a pair of single width, single inlet, blower housings spaced from each other and arranged with coaxial inlets disposed on opposing or adjacent sides thereof. A pair of adjacent inlet boxes are disposed between, and connected to, said

blower housings so that they communicate with the inlet openings in their respective housings. A shaft, which extends through said blower housings and said inlet boxes coaxially with said inlet openings, is supported near its opposite ends upon a pair of bearing assemblies located on the remote sides of said blower housings. A pair of single width, single inlet, blower wheels are mounted upon said shaft within their respective housings and, therefore, adjacent, respectively, to the bearing assemblies. The outlet of one blower housing and the inlet of the inlet box associated with the other blower housing preferably open in substantially the same direction and are interconnected by a U-shaped duct. Thus, the air and pressure produced by the one fan unit are transferred to the inlet of the other fan unit for stepping up such pressure.

Detailed construction

As shown particularly in Figures 1 and 3, the two-stage blower assembly 10 is comprised of two single width, single inlet, blower housings 11 and 12 and two adjacent inlet boxes 13 and 14, which are disposed between, and are associated respectively with, said housings 11 and 12, said housings and inlet boxes being fabricated primarily from sheet-form materials, as shown in Figure 3. The mutual side walls 16 and 17 between the corresponding blower housings and inlet boxes are provided with coaxial inlet cones 18 and 19. The blower housings and inlet boxes are all connected together and said inlet boxes have a common intermediate wall 21. A shaft 22 extends completely through both inlet boxes and both blower housings coaxially with the inlet cones 18 and 19. An appropriate shaft seal 20 (Figure 3) may be provided in the wall 21 around the shaft 22 for sealing purposes. Said shaft is rotatably supported near its opposite ends by means of the bearings 23 and 24, which may be substantially conventional in construction and which are mounted upon means, such as the pedestals 26 and 27. The shaft 22 extends beyond the pedestal 27, in this particular embodiment, for either direct or indirect connection to a conventional prime mover of any convenient type, which is indicated schematically at 28. A pair of single inlet blower wheels 31 and 32 are each supported upon the shaft 22 by means of a hub, such as that shown at 33 on the wheel 32. Said wheels 31 and 32 are positioned upon said shaft 22 so that the inlets thereof are adjacent to the corresponding inlet cones 18 and 19. The blower housing 11, inlet box 13 and wheel 31 comprise a first blower unit 34 in the blower assembly 10, whereas the blower housing 12, inlet box 14 and wheel 32 comprise a second blower unit 35 in said blower assembly 10.

The common wall 21 between the inlet boxes 13 and 14 is, in this particular embodiment, sloped with respect to the axis of the shaft 22, and the inlet openings 37 and 38 in the inlet boxes 13 and 14, respectively, enter opposite sides, such as, for example, the bottom and the top, of the assembly 10, where said common wall 21 is at the maximum divergency with respect to the particular inlet box. This arrangement materially reduces the space required by said inlet boxes between the blower housings and thereby permits the use of a smaller shaft 22 than would otherwise be permissible.

In this particular embodiment, the inlet opening 37 is in the bottom of the inlet box 13 and the inlet opening 38 is in the top of the inlet box 14, and both blower housings 11 and 12 have upwardly discharging outlets 40 and 41, respectively. The discharge directions of the two blower housings 11 and 12 may vary with respect to each other. However, because the two wheels 31 and 32 are always rotating in the same direction, the rotational directions of their discharge will always be the same, that is, they will both have either a clockwise or a counterclockwise direction of discharge. The direction of discharge from the outlet 40 of the first blower unit 34 will be substantially the same, hence on the same side of the assembly 10, as the direction of entry of the inlet opening 38 of the inlet

box 14 associated with the second blower unit 35. Thus, the outlet 40 can be easily connected to the inlet opening 38 by means of a U-shaped connector duct 42. In this particular embodiment, said duct 42 has an expanding cross-section because the area of said outlet 40 is smaller than the area of said inlet 38. However, the area of said outlet 40 may be the same as, or larger than, the area of said inlet 38.

10

Operation

The operation of the two-stage blower assembly 10 commences with air being drawn through the inlet opening 37 (Figure 3) in the inlet box 13 and thence passing through the inlet cone 18 where it enters the inlet of the blower wheel 31 and is driven thereby through the outlet 40 in the blower housing 11. The air leaving the outlet 40 is conveyed to the inlet opening 38 by the expanding connector duct 42 which, in this embodiment, reduces the air velocity, thereby increasing the efficiency of the first blower unit 34. Such air, having thus reached the inlet box 14 of the second blower unit 35, is drawn thereby through the inlet cone 19 where the blower wheel 32 discharges such air through the outlet opening 41 into any convenient, conventional, duct system, not shown.

20 It has been found that, by use of the two-stage blower assembly 10 substantially as disclosed, air departing from the outlet 40 in the first stage blower unit 34 at a given pressure and volume will depart from the outlet 41 in the second stage blower unit 35 with its pressure approximately doubled. It has also been found that, by having the outlet 40 and inlet opening 38 face in substantially the same direction, the air moving through the connector duct 42 enters the inlet cone 19 without rotational components about the shaft 22, which components can materially reduce the performance of the second blower unit 35. This is due to the fact that the velocity component of the air flow from the outlet 40 to the inlet cone 19 is in a direction substantially parallel with a plane including the axis of said shaft and parallel with the direction of discharge from said outlet 40.

25 The fact that the wheels 31 and 32 are disposed very close to the bearings 23 and 24, respectively, makes it possible to use a shaft 22 which is considerably smaller in maximum diameter and, therefore, in weight than the shaft would have to be if the blower wheels were mounted, according to present teachings, at or near the center thereof. Accordingly, the bearings 23 and 24, as well as their support pedestals 26 and 27, may also be substantially smaller than would otherwise be required if said wheels were mounted at the center of the shaft. Because the blower wheels 31 and 32 are mounted adjacent to the ends of the shaft, where the shaft has its smallest diameter, the wheel hubs 33 may also be of a minimum size and weight. This not only permits the use of a shaft 30 having a minimum size and weight, but also results in a minimum of interference with the air flow through the fan wheels and; therefore, the best performance available.

35 In order to meet specific installation requirements, the outlet 40 of the first blower unit 34 may face in a different direction, such as sidewardly, than the outlet opening 41 in the second blower unit 35. However, the outlet 40 and inlet opening 38 will normally face in substantially the same direction to eliminate undesirable rotational components in the air flow. Further, where other factors, such as ease of fabrication, are more important than the maximum saving in cost and space requirements, the common wall 21 may be substantially perpendicular to the axis of the shaft 22, thereby requiring an increase in the space occupied by the inlet boxes 13 and 14. Such a condition may occur where it is desirable to have the inlet opening 37 at an angle of 90°, instead of 180° as shown, to the inlet opening 38. However, the most desirable arrangement includes a sloping common wall 21.

40 Figure 4 illustrates a multiple blower assembly 50, comprised of centrifugal blowers 51, 52 and 53 and inlet

75

boxes 55, 56 and 57. The blowers 51 and 52 and the inlet boxes 55 and 56 may be arranged in substantially the same manner as that set forth hereinabove with respect to the assembly 10 of Figure 1. However, the outlet of blower 52 is connected by the duct 58 to the inlet box 57 associated with the blower 53, thereby producing the three-stage blower assembly 50. The blower wheels (not shown) within the blowers 51, 52 and 53 may be supported upon a single shaft 59, which is supported upon the bearings 61 and 62.

Although particular, preferred embodiments of the invention have been disclosed hereinabove for illustrative purpose, it will be understood that variations or modifications of such disclosure, which lie within the scope of the appended claims, are fully contemplated.

I claim:

1. A multi-stage, centrifugal blower assembly for moving a gas, comprising: first and second, single inlet and single outlet, centrifugal blower housings spaced from each other and having axially aligned inlet openings on the opposing sides thereof; a pair of inlet cones secured respectively to said housings concentric with and adjacent to said inlet openings therein; first and second adjacent inlet boxes disposed between, and communicating respectively with, the inlet openings in said housings, said inlet boxes having single inlet openings facing in substantially opposite directions, the inlet opening of the second inlet box facing in substantially the same direction as the outlet opening of the first blower housing, said housings and inlet boxes being fabricated primarily from relatively thin materials, whereby the combined length of said housings and inlet boxes, axially of said inlet cones, is held to a minimum; a shaft extending through said blower housings and said inlet boxes coaxially with said cones; bearing means adjacent to the remote, outer sides of said housings and rotatably supporting said shaft, said bearings providing the sole support of said shaft therebetween; a pair of centrifugal blower wheels supported entirely upon said shaft and rotatable therewith within said blower housings, each wheel being disposed between and adjacent to, but spaced from, one of said bearing means and the adjacent one of said cones; and a substantially U-shaped connecting duct extending between the outlet opening of said first blower housing and the inlet opening of said second inlet box.

2. The structure of claim 1 wherein said inlet boxes have a common, intermediate and relatively thin, substantially planar wall which diverges with respect to the opposing wall of each box toward the inlet opening in each box, said common wall having a central opening through which said shaft is freely received; wherein the axis of curvature of said connecting duct is substantially perpendicular to the axis of said shaft, whereby air enters said second blower housing substantially without rotational components about said axis of said shaft; and wherein said U-shaped connector duct has a greater cross-sectional area at its outlet end, adjacent to the inlet opening of said second inlet box, than it does at its inlet end, adjacent to the outlet opening of said first blower housing.

3. A two-stage, centrifugal blower assembly for moving air, comprising: first and second single inlet and single outlet, centrifugal blower housings spaced from each other and having coaxial inlet openings on the opposing sides thereof; a pair of inlet cones secured respectively to said housings adjacent to and concentric with the inlet openings thereof, said cones extending into said housings; first and second adjacent inlet boxes disposed between, and communicating respectively with, the inlet openings in said housings, each inlet box having a single inlet opening disposed in the periphery thereof, the inlet openings

60
65
70

of said boxes facing in substantially opposite directions and the inlet opening of said second box facing in substantially the same direction as the outlet opening of the first blower housing, the walls of said housings and inlet boxes being fabricated primarily from sheet-form materials, whereby the combined length of said housings and inlet boxes, axially of said inlet cones, is held to a minimum, said inlet cones extending into said inlet boxes and said housings; a shaft extending through said blower housings and said inlet boxes coaxially with said cones; bearing means adjacent to the remote, outer sides of said housings rotatably supporting said shaft near the ends thereof, said bearings being located at a minimum distance from each other and providing the sole support for said shaft; a pair of centrifugal blower impellers secured to and supported entirely by said shaft for rotation respectively within said blower housings, said impellers being adjacent respectively to said bearing means, and each impeller having an inlet rim concentric with, adjacent to and spaced from one of said cones; and a substantially U-shaped connecting duct extending between the inlet opening of said second box and the outlet opening of said first blower housing.

4. A multi-stage, centrifugal fan assembly for moving a gas, comprising: first and second, single inlet and single outlet, centrifugal fan housings spaced from each other and having axially aligned inlet openings on the opposing sides thereof; a pair of annular structures secured respectively to said housings concentric with and adjacent to said inlet openings therein; first and second adjacent inlet boxes disposed between, and communicating respectively with, the inlet openings in said housings, said inlet boxes having single inlet openings facing substantially radially from the axis of the inlet openings of said housings in directions displaced circumferentially from each other at an angle in excess of 90 degrees around said axis of the inlet openings of said housings, the inlet opening of the second inlet box facing in substantially the same direction as the outlet opening of the first fan housing, said housings and inlet boxes being fabricated primarily from relatively thin materials, whereby the combined length of said housings and inlet boxes, axially of said annular structures, is held to a minimum; a shaft extending through said fan housings and said inlet boxes coaxially with said annular structures; bearing means adjacent to the remote, outer sides of said housings and rotatably supporting said shaft, said bearings providing the sole support of said shaft therebetween; a pair of centrifugal fan wheels supported entirely upon said shaft and rotatable therewith within said fan housings, each wheel being disposed between and adjacent to, but spaced from, one of said bearing means and the adjacent one of said annular structures; and a substantially U-shaped connecting duct extending between the outlet opening of said first fan housing and the inlet opening of said second inlet box.
